FUEL CONTROL FOR INTERNAL COMBUSTION ENGINES

Max Dach, Flushing, N. Y.

Application February 2, 1937, Serial No. 123,569

5 Claims. (Cl. 123—102)

This invention relates to an attachment for internal combustion engines by means of which the fuel inlet to the engine can be entirely and completely closed when desired and the vacuum in the intake as well as the vacuum in the manifold, if such is used, can be broken when desired. The closing of the fuel inlet and breaking of the vacuum in the fuel inlet or manifold, or both, may be accomplished by the vehicle that is being driven by the internal combustion engine reaching a predetermined maximum speed or when the engine is running above a predetermined speed with the throttle open, or when the fuel is intended to be shut off and the vehicle is driving the engine; or the momentum of the engine itself is driving it.

The invention will be understood from the description in connection with the accompanying drawings, in which Fig. 1 is a somewhat diagrammatic side view showing an illustrative embodiment of the invention; Fig. 2 is a vertical section through the fuel inlet; Fig. 3 is a section similar to Fig. 2 showing a modification; Figs. 4, 5 and 6 are sections showing modifications of the valves shown in Figs. 2 and 3; Figs. 7 and 8 are side views, partly in section, of modifications of Fig. 1; and Figs. 9, 10, 11, 12 and 13 are side views, partly in section, showing other modifications.

30 In the drawings, reference character 1 indicates an intake manifold of an internal combustion engine that is connected to a carburetor by the inlet 2 in which the throttle 3 is placed and connected by the rod 4 to the foot pedal or accelerator pedal in the usual way.

The generator 5, shown diagrammatically, may be of the usual sort that is installed in connection with automobile engines, having the cut-out 6 so that the battery 7 is cut in as soon as the engine reaches a sufficiently high speed. A lead 8 extends from the cut-out 6 to a winding of the solenoid 9, which solenoid has a movable or reciprocating core. A lead 10 extends from the other side of this winding to the ground and a switch 12 is shown in this lead, this switch 12 being attached to the linkage, such as the foot pedal 13, for example, that controls the throttle 3.

Lead 14 may also be provided from the lead 50 10 to a speed limiting device of any of the usual sorts, such for example, as that designated by reference character 15, that may be connected either to the engine or to the driven mechanism of the car. This speed limiting device 15 may be 55 one of the sorts now in use that is capable of

being set at maximum permissible speeds. When the pointer 16 of the speed limiting device 15 reaches the limit for which the speed has been set connection is completed from the lead 10 to the lead 17 which is connected to the ground. 5

The movable core 18 of the solenoid 9 is connected by the link 19 to the arm 20 on the shaft 21 of a valve in the inlet 2. The arm 20 on the shaft 21 is connected to one end of a tension spring 23, the other end of which spring 10 is fixed in position. A stop 24 is provided for the arm 22 so that when the solenoid 9 moves the arm 20 against the stop 24 the valve 25 carried by the shaft 21 is closed.

The valve 25 is a cylindrical rotary valve and 15 is shown in Fig. 2 in its closed position. A passageway 26 is provided in this valve so that when it is turned sufficiently from the position shown in Fig. 2, communication is established through the fuel inlet to the intake manifold. An opening 27 is provided from the passageway 26 and an opening 28 is provided through the side of the valve casing 29, so that communication is established between the atmosphere and the intake manifold when the valve 25 is closed, thus breaking 25 the vacuum. At the same time, the fuel inlet is entirely shut off with the valve 25 in the position shown in Fig. 2.

In the modification shown in Fig. 3, a partition 30 is provided in the valve, thus leaving two 30 parallel passageways 26' and 26'' and openings 31 and 32 respectively are provided from these passageways to the surface of the valve. Openings 33 and 34 are provided in the valve casing 29 similar to the opening 28 so that the vacuum 35 in the intake 2, as well as the vacuum in the intake manifold 1, is broken when the valve is closed. An opening 35 having a screw 36 for adjusting the size thereof, may also be provided in the valve casing 29 to communicate with an 40 opening 37 near the surface of the valve 25a. This opening may be used for admitting another fuel or deodorant if desired.

In the modification shown in Fig. 4, a valve 25b is shown which when placed in the inlet 45 2 will entirely shut off the fuel in its closed position without breaking the vacuum in the inlet or the manifold. The valve 25c shown in Fig. 5 is provided with an opening 39 and an opening 40 so that when placed in the valve casing shown 50 in Fig. 3, the vacuum in the inlet will be quickly broken and that in the intake manifold can be broken as gradually as desired by adjusting the screw 36.

In the modification shown in Fig. 7 the core 55

of the solenoid 9 is connected to the arm 43 of a three way valve 44 in the pipe 45 leading from a compressed air tank. When the solenoid operates to open the valve 44 the air forces the piston 46 of the cylinder 41 to the right. This piston is connected by an arm 48 and link 49 to the arm 20 of the valve in the inlet 2 so that this valve is closed, when the solenoid 9 is energized in either of the ways already indicated.

10 A compression spring 49 opens the valve 20 when the valve 44, which is normally kept in its closed position by a spring or otherwise, is turned to the position to permit the air to escape from the cylinder 41.

15 The parts shown in Fig. 8 are somewhat similar to those shown in Fig. 7, except that the three way valve 44 is installed in a pipe 50 leading from the intake manifold to the cylinder 51 which is provided with a piston 52 with a compression spring 53 behind it. Suction in the cylinder 51 when the valve 44 is opened causes the valve in the inlet 2 to be closed, and the spring 53 opens this valve when the vacuum is released.

20 Instead of using a cylindrical valve, as indicated above, a butterfly valve may be used. The cylindrical valves already described, as well as the butterfly valves about to be described, can be connected by linkage mechanism to the accelerator pedal or other operating mechanism, 30 and the valve 3 in Fig. 2 may be used as a choke valve, while the other valves are operated by the accelerator pedal or otherwise.

35 In the modification shown in Fig. 9, a butterfly valve 55 is operated in a manner similar to the way the valve 25 already described is operated, but instead of having openings through the valve itself for breaking the vacuum in the fuel inlet and the manifold, auxiliary valves are provided in the inlet. Two of these valves 56 are shown 40 which are normally seated against the valve seats 57. When the valve 55 is closed its edges strike pins 58, passing through the walls of the inlet. These pins are connected to levers 59 pivoted on lugs 60 and operating the valves 56. 45 Tension springs 61 normally keep the valves 56 closed.

50 In the modification shown in Fig. 10 the valve 65 is the throttle valve which is operated by the accelerator pedal or otherwise. The valve 65 closes completely when the foot is taken off of the accelerator and the solenoid 9' is energized due to the closing of the switch 12 (Fig. 1). Provision is made for opening this valve 65 to its idling position when the engine slows down sufficiently to cause the solenoid 9' to be almost demagnetized. The intake vacuum is also broken while the engine is decelerating.

55 In Fig. 10 a lug 66 is provided on the valve 65 and core 18' of the solenoid 9' carries an adjustable pin 67 which can strike the lug 66. The core 18' also carries a head 68 that is faced with rubber or other material that will make an air tight fitting against the inlet 2, and the spring 70 is interposed between the head 68 and the end of the solenoid 9'. In the operation of the modification shown in Fig. 10, when the solenoid 9' is energized by the operator lifting his foot off of the accelerator pedal and the engine is running above a predetermined minimum speed, 60 the core 18' of the solenoid is withdrawn to permit the valve 65 to close completely and at the same time permit air to enter through the opening 71 to break the vacuum. As soon as the engine slows down sufficiently to practically 65 deenergize the solenoid 9' the spring 70 pushes

the head 68 against the inlet 2, thus closing the air inlet 71 and causing the pin 67 to strike the lug 66 and open the valve 65 to the idling position.

70 In the modification shown in Fig. 11, the throttle valve 75 is connected by an arm 76 to the link 77 that is connected to the core of the solenoid 9'. If desired, a manually controlled valve, which may be similar to the valve 3 shown in Fig. 2, may be installed in the inlet 2 and be used as a choke valve, as already described. The arm 76 is also provided with an arm 78 having adjustable pin 79 which strikes a spring pressed closure 80. This closure 80 is pivoted on a pivot 81 on which a spring 82 is mounted tend- 15 to turn the closure 80 in a clockwise direction as seen in Fig. 11. An air inlet 83 is provided in the wall of the inlet 2 and has a flat side against which the closure 80 normally rests to close it. The solenoid 9' in Fig. 11 is energized either by 20 the operator lifting his foot from the accelerator pedal while the engine is running above a predetermined minimum speed, or by the car or engine exceeding a predetermined maximum speed. The solenoid 9' comprises a winding 84 25 in which a hollow core of magnetic material 85 moves and is connected to the link 77. The linkage mechanism 13' which may carry the switch 12, as already described, has its outer end enlarged as shown at 86 and a compression 30 spring 82' is interposed between this enlarged end and the closed end of the hollow core 85. In this modification when the solenoid 9' is energized the core 85 is drawn inwardly, thus closing the valve 75 even if the accelerator pedal 35 is still in its running position. At the same time the pin 79 on the arm 78 strikes one end of the closure member 80, that is pivoted on the pivot 82, and thus opens the air inlet 83 and breaks the vacuum in the intake manifold 1. However, 40 when the speed of the vehicle or of the engine decreases sufficiently to cause the solenoid 9' to be practically deenergized the spring 82' opens the valve 75 to the idling position, or this valve stops at whatever position it may be held by the 45 operator.

45 In the modification shown in Fig. 12 the valve 88 in the inlet 2 may be completely closed in any of the ways described above, or a cylindrical valve may be used instead of the butterfly type. 50 A choke valve similar to the valve 3 of Fig. 2 may, if desired, be used in the inlet 2 of this modification, as stated above. The valve 88 is to be closed completely either by the engine or car exceeding a predetermined maximum speed or 55 by releasing the accelerator, as already described. In this Fig. 12 another way of opening the valve to its idling position is shown which operates after the engine has slowed down sufficiently.

60 The arrangement shown in this Fig. 12 comprises a T-shaped connection 89 to the inlet manifold 1. It has one of its arms 89' externally threaded and its other arm 89'' is threaded both externally and internally. A thimble 90 is screwed upon the arm 89'' and this arm is provided with an internal plug 91 which can be adjusted in position and held in its adjusted position by the lock plug 92 which may be provided with a slot 93 to be reached by a screw driver when the cap 90 is removed. A valve 94 is 70 pressed against the seat 95 by a spring 96 interposed between the valve and the plug 91. An internally threaded extension 97 is provided on a housing 98 in which a diaphragm 99 is mounted. The extension 97 is internally threaded and is 75

therefore adjustable on the arm 89' and a lock nut 100 is provided for holding it in adjusted positions. An opening 88' is provided in the wall of the housing 88 leading into the connection 88 and an air bleeder opening 88' is provided through the diaphragm 88. A rod or pin 101 is connected to the diaphragm 88 by means of nuts 102 and extends through an opening 103. The pin 101 carries a stop 104 that is preferably provided on its outer face with packing material to fit against the outside of the inlet 2 and close the opening 105 through which this pin extends. A compression spring 106 is interposed between the side of the housing 88 and the stop 104. The pin 103 strikes a lug 107 on the valve 88 and opens this valve to an adjustable idling position, when the spring 106 presses the closing member 104 against the inlet 2.

The device shown in Fig. 12 normally operates to keep the closing member 104 pressed against the inlet 2, but when the vacuum in the manifold 1 becomes too high, due to existing speed of the engine, for example, the valve 94 is withdrawn from its seat 95 and the vacuum on the right hand side of the diaphragm 88 pulls the pin 101 and closing member 104, thus breaking the vacuum and slowing down the speed. The point at which the vacuum operates in this way can be adjusted by adjusting the plug 91 and the extension 97 on the T-connection 88. The bleed of air through the air bleed opening 88' permits the spring 106 to move the closing member 104 to close the opening 105 after the valve 94 is closed.

In the modification shown in Fig. 13 the valve 110 in the inlet 2 is shown as a butterfly valve that is operated by the shaft 111. An arm 112 is attached to the shaft 111 and this arm 112 is connected to the accelerator by the connection indicated somewhat diagrammatically at 113. An extension 114 is provided on the arm 112 and an adjustable set screw 115 is provided near the end of this extension.

An opening 116 is provided from the atmosphere or a source of gas or deodorant into the inlet 2. This opening may be similar to the air inlet 83 shown in Fig. 11, or it may be a pet cock or other well known device that can be opened and closed. An arm 117 is pivoted on a pivot 118 around which a spring 119 is provided for normally causing one side of the arm 117 to close the opening 116. A lever 120 is pivoted at 121 so that one end of this lever strikes one end of the arm 117 and the other end of this lever is pivoted as shown at 121 to the core 122 of the solenoid 123 which is similar to and is operated in a manner such as has been described above in connection with the other modifications.

In the operation of the device shown in Fig. 13,

when the operator removes his foot from the accelerator the valve 110 is closed in the usual way, except that the accelerator is so arranged that this valve is entirely closed. This closing of the throttle 110 energizes the solenoid 123 in the way already described, whereupon the core 122 turns the lever 120 so that its lower end turns the arm 117 anticlockwise against the tension of the spring 119, thereby establishing connection from the air (or other source) with the inlet manifold 1, thereby breaking the vacuum. When the car slows down sufficiently to practically deenergize the solenoid 123 the spring 119 turns the arm 117 sufficiently to close the opening 116 and simultaneously turns the lever 120 so that its upper end strikes the set screw 115, thereby opening the valve 110 to its idling position.

I claim:

1. In an internal combustion engine having an intake manifold, a fuel inlet leading into said manifold, means to stop all fuel from passing through said inlet and break the vacuum in said manifold either when said throttle is released or when a member driven by said engine reaches a predetermined maximum speed, and means to regulate the time it takes for said vacuum to become broken.

2. In an internal combustion engine having an intake manifold, a fuel inlet leading into said manifold and means to stop all fuel from passing through said inlet and establish communication between the atmosphere and said manifold at a predetermined maximum speed with the throttle open.

3. In an internal combustion engine having an intake manifold, a fuel inlet leading into said manifold and means to stop all fuel from passing through said inlet and break the vacuum in said manifold at a predetermined maximum speed with the throttle open, and means to regulate the time it takes for said vacuum to become broken.

4. In an internal combustion engine having an intake manifold, a fuel inlet leading into said manifold and means to stop all fuel from passing through said inlet and establish communication between the atmosphere and said manifold when the throttle pedal is released at a predetermined maximum speed.

5. In a device of the character described, an internal combustion engine, a fuel inlet for said engine, a throttle valve in said inlet, magnetically operated means to close said throttle completely when fuel is not needed with the engine running and means to open it partially when idling speed is reached.

MAX DACH.
